DESIGN FOR AN EGG RACK

Sophie B. Ernster, West Los Angeles, Calif.

Application August 23, 1945, Serial No. 121,593

Term of patent 7 years

(Cl. D44—1)

To all whom it may concern:

Be it known that I, Sophie B. Ernster, a citizen of the United States and resident of West Los Angeles, county of Los Angeles, State of California, and whose post-office address is #10442 Eastborne Ave., West Los Angeles 26, California, have invented a new, original, and ornamental Design for Egg Racks, of which the following is a specification, reference being had to the accompanying drawing, forming a part thereof.

Fig. 1 is a plan view of an egg rack showing my new design.

Fig. 2 is a side elevational view of the egg rack.

Fig. 3 is a bottom view of the rack.

Fig. 4 is an end elevational view of the rack.

I claim:

The ornamental design for an egg rack, as shown.

SOPHIE B. ERNSTER.
